United States Patent Office.

REBECCA GILKINSON, OF NEW YORK, N. Y.

Letters Patent No. 111,195, dated January 24, 1871.

IMPROVEMENT IN MEDICAL COMPOUNDS FOR THE CURE OF RHEUMATISM.

The Schedule referred to in these Letters Patent and making part of the same.

To all whom it may concern:

Be it known that I, REBECCA GILKINSON, of the city, county, and State of New York, have invented a new and useful Improvement in Medical Compound; and I do hereby declare that the following is a full, clear, and exact description thereof, which will enable others skilled in the art to make and use the same.

This invention and discovery relates to a new and useful improvement in a liniment for curing rheumatism and similar diseases, and consists in a compound composed of the ingredients and in about the proportions hereinafter named.

In carrying out my invention, I, in the first place, boil four ounces of dry catnip-leaves in three quarts of water until the quantity is reduced or evaporated to two quarts.

I then add to this decoction one quart of pure alcohol; four ounces of carbonate soda; two ounces of Cayenne pepper, and two ounces of English mustard.

These ingredients are well stirred and mingled together, forming a most valuable liniment for external application in cases of rheumatism and all similar affections of the human body.

Having thus described my invention,

I claim as new and desire to secure by Letters Patent—

The above medical compound, substantially as described.

REBECCA GILKINSON.

Witnesses:

ALEXANDER LINEN,
T. B. MOSHER.
